Carpets

UNITED STATES PATENT OFFICE.

ALBERT COWELL, OF KIDDERMINSTER, ENGLAND.

DESIGN FOR A CARPET-PATTERN.

Specification forming part of Design No. 5,713, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates more particularly to the new outline and decoration of a symmetrical shield, which constitutes the chief figure of a carpet-design, and which contains a bouquet of roses and other flowers set in a vase. The shield is surmounted by a sort of mantel carrying flowers on its crown, as shown.

I claim as my invention—

The design for a carpet, decorated as herein shown and specified.

ALBERT COWELL.
